E. M. Matten.
ATTORNEY.

UNITED STATES PATENT OFFICE

WALTER F. HEROLD, OF UPPER MONTCLAIR, NEW JERSEY, ASSIGNOR TO THE BASICK COMPANY, OF BRIDGEPORT, CONNECTICUT, A CORPORATION OF CONNECTICUT

CASTER SOCKET

Application filed November 4, 1926. Serial No. 146,123.

The present invention relates to improvements in caster sockets, particularly for use with articles of furniture having tubular metal legs, as hospital beds, and the like, and into which the caster pintle is removably inserted and supported in a manner to have free pivotal movement about its vertical axis.

Heretofore such sockets have been held in place within the leg by a friction fit, the tightness of such fit being depended upon to retain it. This has proved unsatisfactory, however, inasmuch as the metal legs are usually cut off in such manner that an in-turned edge or bur is formed at the base of the leg, so that, while the socket was tightly held by this edge it was prevented from engaging the inner surface of the leg, and an insecure, wobbly fit resulted. Easy removal was practically impossible, due to this tight friction fit. Also there was considerable variation in size, due to the tolerances obtaining in this type of article, so that it was practically impossible to maintain a uniform fit.

It is proposed, in the present invention, therefore, to provide a socket including an auxiliary socket retaining spring means, which will securely and reliably retain the socket in the leg, irrespective of the turning-in of the end of the leg, and variation in size, and which will permit the full strength of the metal of the socket frame to be utilized for support between the pintle and the furniture leg.

A further object is to provide such means which may be conveniently assembled with the socket, without greatly adding to its cost.

With the above and other objects in view, embodiments of my invention are shown in the accompanying drawings, and these embodiments will be hereinafter more fully described with reference thereto, and the invention will be finally pointed out in the claims.

In the drawings:

Fig. 1 is a side elevation of a caster socket, according to the present embodiment of the invention;

Fig. 2 is a front elevation of the same, and

showing it inserted in a tubular furniture leg, the latter shown in section;

Fig. 3 is a vertical sectional view showing the assembled caster and socket attached to the furniture leg;

Fig. 4 is a top plan view of the socket;

Fig. 5 is a bottom plan view thereof;

Fig. 6 is perspective view showing the socket base, pintle retaining spring means, and socket retaining spring means in separated superimposed relation;

Fig. 7 is a side elevation of a socket, according to a modified form of the invention;

Fig. 8 is a front elevation thereof; and

Fig. 9 is a front elevation, partly in section, of a further modified form of the invention.

Referring to the drawings, the caster socket, according to the present embodiment of the invention, is adapted to be inserted in the tubular metal leg of post 10, as shown in Figs. 2 and 3, the lower end of this leg being usually turned-in, as at 11, in practice, due to the method of cutting off, as for instance, by sawing.

The socket comprises a frame member formed from sheet metal bent upon itself and pressed to shape to provide a top bearing socket portion 12 having a center bearing 13 in the form of an indenture, pinched together ears 14 and 15 at diametrically opposite sides of said top portion, and side legs 16 and 17, shouldered adjacent the top portion, and pressed to form portions of a cylinder adapted to fit into the leg. At their lower ends the legs are flanged outwardly, as at 18 and 19, to form shoulders adapted to be disposed beneath the end of the leg, and bent downwardly and inwardly, as at 20 and 21, to clampingly engage the periphery of a circular base disc 22, this disc being centrally apertured, as at 23, to receive the caster pintle. Upon this base are assembled the pintle retaining means and the socket retaining spring member.

The socket retaining spring member consists of a circular base 24 of smaller diameter than the disc 22, provided with a central aperture 25 slightly larger than the aperture 23

of the disc 22, and having upwardly extending, outwardly inclined, spring arms 26 and 27 bent therefrom at diametrically opposite sides, said arms being curved inwardly at their upper ends. The base 24 is adapted to be engaged upon the base 22 in concentric relation with the spring arms disposed in the spaces between the side legs of the socket frame, and projecting at each side to an extent greater than the inner diameter of the furniture leg. Registering slots 28, 29 and 30, 31 are provided in the bases 24 and 22 for the purpose of securing the pintle retaining means to the base 22, as will presently more fully appear, the spring member being interposed at its base between said means and said base 22, and thus assembled and secured.

The pintle retaining means comprises a cup member 32 having a central opening 33 in line with the aperture 23, and secured by projecting lugs 33 and 34 inserted through the slots of the bases 24 and 22 and bent over upon the under surface of the base 22. Within this cup member there is loosely engaged and retained a split spring ring 35 having an inner diameter smaller than that of the openings 23 and 25, and an outer diameter smaller than the inner diameter of the cup member, this spring adapted to yieldingly retain the caster pintle, as will presently more fully appear.

The detachable caster consists of the usual horn 36, having a caster wheel 37 rotatably carried therein upon an axle 38, and having a pintle 39 secured in its upper transverse portion; the lower end of the pintle having a flange or shoulder 40 engaging the upper surface of the horn. At its upper end the pintle is provided with a central recess 41 adapted to rotatably engage the top bearing 13 of the socket frame. The diameter of the pintle is such that it will expand the ring 35 and be frictionally held thereby against dropping out of the leg, the ring being snugly held about the pintle and being freely rotatable within the cup member 32.

The socket is inserted in the leg as shown in Figs. 2 and 3, the spring arms expanding against the inner surface thereof above the lower end, so that even with a very decided turning-in of the leg end the springs will securely and reliably retain the socket. The socket may, on occasion, be a loose fit in the leg, but will be securely retained by the spring arms.

The manner of supporting the pintle retaining spring ring independently of the socket frame, and the provision of the auxiliary socket retaining spring means permits the frame to be formed from one piece, of any desired thickness, form, metal characteristics, or strength, without weakening it or adapting its form by the attachment or formation therein of pintle and socket retaining means, so that the full strength of the

frame member may be utilized for forming a support between the pintle and the furniture leg.

In Figs. 7 and 8 I have illustrated a modification, in which the socket retaining spring means consists of a spring wire comprising a transverse top portion 42 disposed over the top of the socket frame, inwardly bent attachment portions 43 and 44 inserted within and clamped by the ear portions 14 and 15, and downwardly extending outwardly curved spring arm portions 45 and 46 adapted to function in a similar manner to the spring arms of the first described embodiment.

In Fig. 9 I have illustrated a further modified form, in which the base plate 47 is provided with a central pintle receiving aperture 48 and a downwardly pressed ring receiving recess 49 surrounding said aperture. The base 50 of the socket retaining spring member is centrally apertured, as at 51, and in its superimposed position upon the base plate 47 forms an annular pocket for the pintle retaining spring ring 52. The base plate 47 and the base 50 of the spring member are secured together by means of lugs 53 on said base plate inserted through slots 54 in the spring base 50, and bent over upon the upper surface thereof, and the edges of both of said bases are clamped by the flanges 20 and 21 of the socket frame member. In the detached relation of the caster pintle, the under surface of the recess 49 may form a slide to engage directly upon the floor.

I have illustrated and described preferred and satisfactory embodiments of the invention, but it will be obvious that changes may be made therein, within the spirit and scope thereof, as defined in the appended claims.

Having thus described my invention, what I claim and desire to secure by Letters Patent is:—

1. In a caster socket, a socket frame adapted to be inserted in an opening in a furniture leg, or the like, and including a top pintle bearing portion and spaced side leg portions, an apertured base portion connected to said frame, pintle retaining spring means carried by said base portion, and spring means disposed in the spaces between said side leg portions adapted to frictionally engage the inner surface of said leg to retain said frame therein.

2. In a caster socket, a socket frame adapted to be inserted in an opening in a furniture leg, or the like, an apertured base portion connected to said frame, and spring means for retaining said frame in the leg, comprising a base portion secured upon said apertured base and spring arm portions bent upwardly from said base adapted to frictionally engage the inner surface of said leg.

3. In a caster socket, a socket frame adapted to be inserted in an opening in a furniture leg, or the like, an apertured base portion

connected to said frame, pintle retaining means carried by said base portion, and spring means carried by said base portion adapted to frictionally engage the inner surface of said leg to retain the frame therein.

4. In a caster socket, a socket frame adapted to be inserted in an opening in a furniture leg, or the like, an apertured base portion connected to said frame, pintle retaining means carried by said base portion comprising an apertured cup member secured to said base portion and a split spring ring loosely disposed and retained in said cup member, and spring means for retaining said frame in the leg, comprising a base portion interposed and secured between said cup member and said apertured base, and spring arm portions bent upwardly from said base adapted to frictionally engage the inner surface of said leg.

Signed at Bridgeport, in the county of Fairfield, and State of Connecticut, this 22nd day of October, 1926.

WALTER F. HEROLD.
